7 Claims. (Cl. 103—87)

1

This invention relates to pumps and more particularly to bilge and sump pumps and to the art of making pumps.

It is among the objects of our invention to provide an electrically driven pump with the electric motor and the hydraulic pumping elements embraced in the same housing wherewith the whole may be entirely submerged under water as in the bottom of the bilge of a vessel and run for long periods of time at high efficiency and without trouble or care. Another object is to provide a pumping unit comprising motor and pump in which the parts are closely coupled and in which the whole of the instrumentality is of low height and small mass whereby to fit conveniently under the floor or deck boards of small vessels. Another object is to provide such a pump and motor assembly in which the motor parts are hermetically sealed and permitted to breathe. A further object is to provide a construction and method wherewith both the driving motor and pump impeller may be correctly centered in alignment within the housing and wherewith the impeller may be properly borne and disposed within the pump chamber and supported both axially and radially with much accuracy on the motor bearings wherewith to obviate outboard bearings, universal joints or loose couplings between the motor and impeller. Another object is to provide method and means wherewith standard, light weight, sheet metal encased inexpensive motors may be efficiently and certainly aligned on aligning surfaces or structures wherewith to mate with corresponding centering surfaces in the housing that embraces the pump to facilitate the desired alignment and concentricity of all the moving parts relative to the housing and more particularly to the surfaces of the pumping chamber of the housing. A further object is to provide a corrosion-proof pump and pump assembly in connection with the non-corrosion-proof parts of a driving motor. A further object is to provide water-proof connection for electrical leads to the driving motor of a motor pump assembly and to provide a flame-proof and explosion-proof construction for the motor with respect to the atmosphere of the bilge or sump in which it may be put to use. Another object is to provide for heat dissipation from the driving motor particularly to the water-cooled parts of the pump portion of the assembly wherewith to facilitate full load operation for long periods of time without injury or substantial loss of efficiency due to deleterious increase in temperature of the driving motor or of the whole assem-

2

sembly. Another object is to provide that the several constituent parts and particularly the pump part of the assembly be easily made to close and maintain tolerances wherewith to achieve and maintain high operating efficiencies and also to reduce the friction load particularly of the fluid seal between the pumping and driving parts thereof.

Another object is to provide for the rapid and secure assembly of the motor and pump parts and rapid and efficient closing and sealing of the housing and particularly that part from which liquid is to be excluded. Another object is to provide simple, inexpensive and highly efficient means for screening out debris and foreign matter from the inlet side of the pump and to provide a substantially self-cleaning screening. Another object is to provide a pump which will be effective to remove water from substantially the ultimate bottom of the bilge or sump.

Another object of our invention is to provide a method of making and assembling a pump for carrying out some or all the preceding objects and more particularly to provide a method of centering, locating and aligning the motor and impeller parts of a pump with respect to their respective working chambers and coacting parts, housings and instrumentalities.

Other objects include providing method and means for making an efficient, compact, long-lived, rugged bilge pump economically and effectively.

Other objects will appear from the following description of the preferred form of our invention reference being had to the accompanying drawings in which Figure 1 is a longitudinal section taken on the broken line 1—1 of Figure 2; Figure 2 is a transverse section taken along the line 2—2 of Figure 1; Figure 3 is an end elevation of the motor with the pilot ring attached and Figure 4 is a fragmentary transverse section taken along the line 4—4 of Figure 1 suggesting the detail of the bayonet lock mechanism and the cover of the housing.

In the preferred form of our invention, illustrated in the accompanying drawing, the assembly of the motor 1 and pump 2 is embraced or contained in a cylindrical housing 3, the upper, as viewed in Fig. 1, end of which is closed by a cover 4 through which pass electrical leads 5, and the lower end of which includes the partition 6 that separates the motor chamber 7 from the pump chamber 8. The extreme lower end of the housing is closed by a plate 9 having a central aperture 10 which comprises the inlet to the

pump. A screen 11 overlies the plate 10, and the extreme bottom end of the housing comprises a flared outwardly and downwardly extending perforate flange or bell 12 on the lower edge of which the pump is adapted to rest in operative position; the perforations 13 comprising a strainer outwardly of the screen 11 wherewith to exclude chips and debris from the screen. As shown in Figure 2 the housing 3 also comprises at a level just above the flange 12 the pump outlet port 14 which preferably terminates in an internally threaded aperture for attachment to a discharge pipe or line.

As shown in Figures 1 and 2 the impeller 16 of the pump is secured to the extreme lower end of the motor shaft 17 with the impeller vanes clearing the inward face of the plate 9 with a desirable close tolerance. The impeller comprises a disc portion 18 from which the vanes thereof preferably rise integrally and comprises a cylindrical body portion 19 which is internally tapped in about the plane of the disc 18 for threaded engagement with the threaded end of the motor shaft 17 and is drilled out internally for close sliding, guiding and centering fit with the smooth cylindrical portion of the motor shaft as at 20. Externally the body portion 19 has a smooth right cylindrical surface normal to the plane of the disc and extending through the central aperture 15 in the partition 6 with wide tolerance and having exterior sliding and sealing contact with the seal 21 which is carried in a stepped shoulder 25 in the partition 6. The seal element 21 which per se is not part of our invention preferably comprises a rubber-like ring with a metallic back up ring 22, all of which has a tight pressed fit in the shouldered portion of the partition 6; the seal presenting a narrow wiping edge contact with the external smooth cylindrical surface of the body of the impeller in stressed, deformed and substantially line contact therewith. Preferably the contacting edge of the seal has an idle diameter approximately ten to fifteen thousandths of an inch smaller than the external diameter of the body of the impeller which admits the assembly of the parts with little effort but maintains a liquid tight seal between the body of the impeller and the partition 6 wherewith to exclude liquid of the pump chamber 8 from entering the motor chamber 7 even though the pump be totally submerged in operation for long periods of time.

The peripheral portion of the impeller disc clears an annular smooth surface 23 with a desirable close free running clearance which is adjustably determined by the position of the impeller on the motor shaft and is maintained by a dome nut 24 lying in the eye of the impeller and having threaded engagement with the extreme end of the motor shaft and locking the impeller at its desired and intended longitudinal position on the motor shaft.

The top cover plate 4 of the assembly is inserted into the open upper cylindrical end of the housing 3 and is preferably secured therein by a bayonet locking structure, see also Figure 4, as between lugs 30 of limited peripheral length integrally formed with the cover and complementary lugs 31 of limited peripheral length integrally formed with the housing. The cover 4 also has an annular groove 32 in which is preferably disposed an O ring seal 33 which makes fluid tight sealing contact with the complementarily disposed annular smooth internal cylindrical surface of the housing 3. Assembly of the cover 75

with the housing is quickly facilitated by axial insertion thereof as permitted by the bayonet lock and lugs and a fraction of a turn in the familiar fashion to effect the bayonet lock between the cover and the housing. Preferably the cover has a radially extending lug 34 which overlies the upper peripheral edge of the housing and has a tapped hole for receiving the threaded portion of the locking screw 35, the smooth end of which enters the small drilled hole 36 in the wall of the housing to secure the cover and housing against rotation after the parts are assembled thereby maintaining the bayonet lock relation between them.

Preferably the upper and outer wall of the cover has a transverse aperture or eye 37 through the lug 33 through which the whole pump assembly may be hooked or suspended for raising or lowering as for example when it is desired to suspend the pump over the side of a vessel to pump water for washing decks or otherwise as may be desired.

As mentioned above the cover 4 is apertured to facilitate the entry of the electrical leads 5; the cover having an internally tapped boss 40 which threadably receives a gland or packing nut 41 which is adapted to force a rubber-like compression washer 42 into a stepped annular shouldered counterbore 43 adjacent the central aperture 44 through which the conduit 45 containing the electrical leads 5 extends. Preferably the conduit 45 is formed of fairly thick wall rubber tube having a close sliding fit with the aperture 44 and which upon compression of the sealing washer 43 is secured in fluid tight sealing relation to the cover 4 wherewith to exclude fluid from passing through the cover via the aperture 44 to or from the motor chamber 7 of the housing. The conduit 45 is of circular contour internally and externally and is, of course, large enough internally to contain the electrical leads 5 with air space therebetween with the result that when the conduit is sealed as aforesaid in relation to the cover and aperture 44 there will be provided an internal air space and passage within the conduit 45 and among the electrical leads 5 to permit the motor chamber 7 to breathe through the conduit 45. To facilitate breathing the conduit 45 will, of course, be longer than the depth of the water or liquid in which the pump is submerged and will be open to atmosphere where the leads protrude from the "upper" end of the conduit. Preferably the conduit 45 will be at least two or three feet long even if the liquid level of the bilge be much less than the length of the conduit so that the breathing passage among the leads and through the conduit will be so long and restricted as to give explosion-proof characteristics to the motor of the pump.

The cover member 4 also performs the function of mounting and/or maintaining the motor 7 in its desired mounted centered and aligned relation to the housing and pump parts. To this end there is formed on the inside of the cover 4 an annular boss 50 defining a central cupped depression 51 in axial alignment with the axis of the motor and shaft thereof, which cup 51 is axially aligned with the aperture 15 in the partition 6 at the opposite end of the housing. In the cup-like depression 51 is disposed a disc or like pad 53 of rubber or rubber-like material of thickness preferably substantially greater than the depth of the cup which upon forcible engagement with the rounded end 52 of the motor casting 70 yieldingly admits the end of the motor cas-

ing to enter the depression 51 while the cover 50 is being forced into the bayonet block as above mentioned wherewith to maintain a strong yielding axial pressure on the central protuberance 52 of the motor urging the motor downwardly as viewed in Figure 1, onto and in tight engagement with the aligned and centered supporting surfaces at the rightward and downward end of the motor and on the partition 6 wherewith to hold the motor securely in its desired position more fully described.

the pole or stator pieces and/or the frame, body or bearing parts of the motor against which the covering cups are intended to have rigid and secure position and bearing. The ring 10 is thus secured or tentatively secured to the end face of the cup 60 is largely dependent upon its frictional contact therewith for security of location with respect to the axis of the motor in part because of the conventional practice of allowing the stay bolts a considerable transverse tolerance in respect to the apertures in the cups through which they pass. At this point of assembly of the ring

To facilitate greater accuracy in mounting and aligning the motor we provide an annular pilot ring 65 preferably made of brass or bronze having an external diameter great enough to overlie the stay bolts 63, see also Figure 3, and of internal diameter somewhat less than the greatest diameter of the spherical protuberance 64. The ring 65 is counterbored at 66 on the face that is to be juxtaposed to the motor and is provided with tapped holes 67 adapted to receive the threaded ends of the stay bolt 63. The first step of our novel method of mounting and aligning the motor is to remove the conventional nuts from the ends of the stay bolts and re-thread the stay bolts into the tapped holes 67 of the ring 65, whereby to draw the ring 65 firmly against the base end of the cup 60 whilst redrawing the cups into their ultimate telescoped positions with the interior of the cups bearing axially and firmly on the internal structure of the motor, not shown, such as the ends of the 55 or similar tool, the exposed end of the shaft 17 preferably being held fast and the protuberance 52 preferably being supported in a live center concentric with the axis of the shaft 17. Thereupon the motor is rotated about its own shaft as 60 by a driving dog engaging the driving notch 71; the driving torque preferably being applied to the ring 65 through the notch since the next step in our method requires machining the face of the ring that looks away from the motor. To 65 this end a lathe tool or other metal removing tool is brought to bear on the end face of the ring 65 wherewith to cut a true flat annular radial face 72 and an intersecting cylindrical surface 73 at right angles thereto of a particular diameter which will correspond approximately exactly with the internal diameter of the cylindrical surface 74 that has been machined with desirable accuracy in the partition 6 of the housing; the partition 6 of the housing also having 75 machined thereon and at right angles to the cy-

cylindrical surface 74 a radial flat annular surface 75 adapted to mate with and have annular tight mating contact with the surface 72 of the ring. In machining the ring the cutting tool will remove the ends or so much of the ends of the stay bolts 63 as were embodied in the material of the ring that was removed by the turning operations, but since the stay bolts still have fair engagement with the remaining portions of the ring and preferably have lock washers under their heads at the opposite end of the motor casing the function and contribution of the stay bolts to the assembly of the ring and motor parts is retained. Since the cylindrical surface 73 of the ring has been turned about the axis of revolution of the motor about its own shaft it follows that when the motor is mounted in the housing with the cylindrical surface 73 of the ring closely fitting the cylindrical surface 74 of the housing that the axis of the shaft will be concentric with the surface 74 of the housing and since the mating radial surfaces 72 and 75 are respectively truly normal to the axis 17 and to the axis of the housing, the axis of the shaft will be strictly coaxial of the housing when the parts are assembled as shown in Figure 1.

As has been suggested, in the manufacture of the housing the surface 74 is machined to be truly coaxial of the housing and similarly the surface 76 within which the seal 21 is centered is made concentric with the surface 75 with the result that the seal 21 and particularly its inner narrow sealing edge will bear concentrically upon the cylindrical surface of the body 19 of the impeller since the latter must be concentric with the axis of the shaft 17 being centered by the close sliding fit between the impeller and the smooth cylindrical portion of the shaft upwardly of the threaded portion thereof. Whilst these controlling surfaces of the partition 6 of the housing are being machined, or in desirable sequence with respect thereto, the other surfaces of the pump chamber and the motor chamber that have to do with the tolerances, clearances and position of the impeller and motor with respect to the housing are machined to desirable location and concentricity. At an appropriate time the surface 23 with respect to which the impeller has running clearance and the surface 80 at the lower end of the housing that locates the lower closure plate 9 are machined to desired axial relationship so that the inner or upper face 81 of the closure plate will have a determinable spacing from the surface 23 which taken with regard to the axial depth of the impeller will afford the desired axial clearances for the radial faces of the impeller when the parts are assembled. In practice we prefer that the impeller clear the face 23 as well as the face 81 by approximately ten to twenty thousandths of an inch and have true parallelism therewith.

To assemble the parts comprising our motor driven pump unit it is practicable to first insert the seal 21 in the counterbore 25 of the partition 6 and then the motor having the ring 65 attached thereto as above described may be inserted from the upper end of the housing, the shaft passing freely through the seal and central aperture of the partition 6 and the ring 65 being brought into the intimate tight truly centered and aligned contact with the mating surfaces of the partition wherewith to square and center the motor and particularly the axis of its shaft 17 with respect to the housing. Thereupon the cover 4 through which the conduit 5 and electrical leads may

freely extend in the absence of the locking nut 41 is brought home to the position shown in Figure 1; the yielding pad 51 forcibly constraining the motor to its desired aligned and centered position in the housing with the axis of the shaft concentric of the surface 74 and normal to the surface 75 of the partition and concentric of the seal 21. Thereafter the conduit 5 may be properly located in the aperture 44 and sealed with respect thereto by the nut 41 and washer 42. If during the foregoing operations of assembly the motor has been resting on its bell shaped flange and base 12, as is convenient, it may then be turned upside down wherewith to expose the pump chamber for free access. Then the impeller 16 may be slid and threaded onto the end of the shaft 17, the extreme end of which is preferably notched for receiving the end of a screw driver to hold the shaft against rotation whilst the impeller is turned on the threads and brought to axial alignment by the cylindrical surfaces fitting as at 20 above described until the smooth face of the impeller contacts the true radial surface 23 of the partition. At this point it may be mentioned in passing that the motor is preferably provided with thrust bearings for the armature or rotor shaft which admit of but limited axial play measurably less than the tolerances allowed between the upper and lower faces of the impeller and the surfaces 23 and 81 between which the impeller is disposed and has its rotation. The impeller having been threaded onto the shaft to the extent of contacting the surface 23 it is then backed off on the threads only sufficiently to give the desired tolerance between the face of the impeller and the surface 23 whereupon the dome nut 24 is threaded onto the extreme end of the shaft locking the impeller to the shaft in the desired final and intended position. Meanwhile the body of the impeller will have entered the seal 21 and assumed a rotatable sealing relation with respect thereto as shown in Figure 1. Alternatively an ordinary lock nut may be threaded onto the shaft 17 whilst the same is held against rotation by a screw driver wherewith to lock the impeller relative to the shaft while holding the shaft against rotation. Then the dome nut 24 may also be threaded onto the end of the shaft to protect the same from contact with the fluid to be pumped. Preferably the dome nut and/or lock nut and dome nut are made of non-corrosive material as will be the material of the housing, impeller and other parts exposed to the fluid to be pumped. In all events the axial clearance between the upper face of the impeller and the surface 23 of the partition may be readily adjusted with micrometric fineness and with much ease because the vanes of the impeller lend themselves to ready visual observation of the number of degrees of rotation by which the impeller is backed up on the screw of the shaft to afford the desired clearance. The operator knowing the pitch of the threads of the screw on the shaft will be able to observe with great accuracy the clearance afforded by backing the impeller on the screw.

After the impeller has been fixed and secured upon the end of the shaft 17 the lower closure plate 9 and the screen 11 are secured to the lower end of the housing by the screws as shown and the assembly is completed. Preferably the screen 11 has annular corrugations to afford an extension of the surface thereof and the screen as a whole is preferably curved to a large spherical radius so that the mid-portion of the screen is

spaced away from the eye of the impeller and the inlet opening 10 as fully as the depth of the bellied bottom flange of the housing comfortably admits without causing the mid-portion of the screen to deleteriously contact or approach the surface upon which the pump rests on the bottom of the bilge or sump where it may be usefully disposed for operation.

It goes without saying that appropriate electrical energy is afforded the motor through the leads 5 wherewith to induce the desired direction and rate of rotation of the impeller, the vanes of which as shown in Figure 2 are preferably appropriately curved and disposed for high efficiency with regard to the desired speed and capacity of the pump.

It is to be noted that the ring 65 has wide flat intimate tight bearing areas with both the cup 60 and the partition 6 as well as the tight intimate edge contact with the protuberance 64, and the ring being of high heat conductivity affords a broad free path for heat to flow from the motor to the partition 6 whence its dissipation to the fluid passing through the pump chamber readily takes place.

It may also be noted that we have found it useful especially in and for testing the seal 24 of our pumps to put a teaspoon full or so of soluble oil in the motor chamber of the pump so that the oil will rest on the seal when the pump is in its normal operating position. The soluble oil emulsifies very rapidly whereby to cause discharged water to take on a milk-like color if any of the oil should pass the seal during a testing period.

While we have illustrated and described preferred forms of our invention and improvements, changes and further improvements will occur to those skilled in the art who come to understand the principles hereof without departing from the spirit or substance thereof and we do not care to be limited in the scope and substance of our patent to the forms herein described for the sake of illustration and exemplification.

We claim:

1. A pump-motor unit comprising a housing having intermediate two oppositely facing ends thereof, a transversely extending centrally apertured but otherwise imperforate internal partition dividing the interior of said housing into a pump chamber on one side thereof and a motor chamber on the other side thereof, both of said chambers being within the confines of the housing, a motor in said motor chamber located therein by engagement of said motor with a seat formed on the proximate surface of said partition, said motor having a shaft extending through said aperture, said housing also having a closure cover for said motor chamber remote from said partition, said cover carrying a resilient pad bearing on the end of said motor and forcibly and yieldingly urging it against said partition, and a pump impeller in said pump chamber rigidly secured to and aligned with said shaft.

2. The combination according to claim 1 with electric leads for said motor and fluid tight sealing means between said cover and said housing, said cover having an aperture for said leads, a water-proof conduit for said leads having one end in said cover aperture and a fluid tight seal between said cover aperture and said conduit, said leads filling less than the whole cross-sectional internal area of said conduit and leaving

5 a small voided area therein for a sufficient length of said conduit that said motor can breathe therethrough but being sufficiently restricted so that flame cannot be propagated therethrough.

3. A motor pump comprising a housing having an axis and an internal partition normal to said axis dividing the interior of said housing into a pump chamber and a motor chamber, said partition having a central aperture coaxial of said axis, a motor in said motor chamber, said motor having an external casing with a partly rounded end surface and a shaft extending through said end surface and through said aperture coaxially of said housing axis, an angled seat on the side of said partition facing said motor chamber comprising a cylindrical surface formed coaxially of said housing axis and an adjacent surface normal to said axis, a separate ring member having complementary seating surfaces formed on one face thereof and seated in the said seat in said partition, said ring also having a sharp annular edge biting into the said rounded end surface of said casing and being located thereon thereby, means securing said ring to the end of said casing with the seating surfaces of said ring respectively coaxial with and normal to the axis of said shaft, and an impeller carried by said shaft in said pump chamber.

4. A motor pump unit comprising a housing having an axis and an internal partition normal to said axis dividing the interior of said housing into a pump chamber and a motor chamber, said partition having a central aperture coaxial of said axis, a motor in said motor chamber, said motor having a casing and a shaft extending through said aperture coaxial of said housing axis, a seat on the side of said partition facing said motor chamber comprising a cylindrical surface formed coaxially of said housing axis, a rigid ring member secured to the exterior of said motor casing adjacent said partition, said member having a fixed complementary cylindrical seating surface formed thereon coaxially of said shaft, said surfaces intimately engaging each other and effecting alignment of the axes of said housing and said shaft, said seat and said ring member each also having mating surfaces disposed in a plane normal to the axis of said housing and said shaft and engaging each other to locate the motor longitudinally in the housing.

5. The unit according to claim 4 in which said member is a one piece element, said motor having stay bolts extending longitudinally through said casing and threadedly engaging said ring member, and screw means also extending through said member into said casing, said bolts and said screw means tightly securing said member in one position on said casing.

6. In combination, a motor pump housing with an apertured transverse partition defining with the interior of said housing a motor chamber, a motor having a sheet metal casing disposed in said chamber, means for securing said motor to said partition including pressure means operatively connected to said housing and said casing and exerting pressure on said casing in a longitudinal direction to urge said casing toward said partition, said motor having a shaft extending through said aperture and being rotatable therein, said casing having surfaces thereon adjacent said partition certain of which are normal to and others coaxial of said shaft, a pump impeller secured to and supported by said shaft on the opposite side of said partition, said partition having surfaces on the side thereof facing said

motor certain of which are coaxial with and others normal to the axis of rotation of said shaft, said first named surfaces intimately engaging the last named surfaces to locate the motor and casing within said housing.

7. The combination according to claim 6 in which said pressure means comprises a closure cover detachably connected to said housing remote from said partition and covering said motor chamber, said cover having a yieldable part engaging the end of said casing remote from said partition, the spacing of said yieldable part of said cover from said partition being slightly less than the spacing of said end of the casing from said partition whereby said cover when so connected to said housing forcibly urges said casing against said partition.
